C. P. MAYHALL

ARCH SUPPORTER

Filed August 18, 1925

C. P. Mayhall,
Inventor

Clarence A. O'Brien.
Attorney

UNITED STATES PATENT OFFICE.

CHARLES P. MAYHALL, OF HARLAN, KENTUCKY.

ARCH SUPPORTER.

Application filed August 18, 1925. Serial No. 51,026.

This invention relates to an improved arch supporter, and it has for its principal object to generally improve upon inventions of this class by providing one of comparative simplicity and durability, which is such in construction as to render it highly efficient in use, and inexpensive to both the manufacturer and the user.

One feature of the invention is a flexible support which exerts an upward pressure against the bones of the foot at all times, and yields when pressure is applied thereto by the foot, and returns promptly to its normal position each time the pressure is relieved, thus allowing the bones to have their natural movements and articulation. This arrangement also permits the muscles, tendons, and ligaments to be properly supported, and yet have natural unrestrained action.

Other features and advantages accompany the invention, and these will become apparent from the following description and drawing.

In the accompanying drawing forming a part of this specification, and in which like numerals are employed to designate like parts throughout the same:

The figure is a perspective of an arch supporter constructed in accordance with the invention, a portion being broken away, and shown in section to disclose the construction more plainly.

Referring to the drawing in detail the reference characters 1 and 2 designate a pair of substantially duplicate metal plates. These plates are arranged one on top of the other, and the lower one 2 is preferably a little longer, and extends beyond the forward end of the top plate. These superposed relatively slidable resilient plates are curvilinearly shaped to conform to the longitudinal arch of the foot, and are confined between two plies of leather 3. These pieces of leather, or other equivalent material, are stitched together around their marginal edges as indicated at 4, and are shaped to fit nicely in a shoe of a given size, and shape. In addition, the two plies of leather are stitched together as at 5 around the two strips of metal to form a retaining pocket for the latter. The pocket is open at its front however, and this allows free relative movement of the two metal plates or strips. Attention is directed to the fact that while the structure is elevated on one side to conform to the inner longitudinal arch of the

foot, the usual flange found on most marketed and patented devices is eliminated. This allows the device to more effectively be used in low shoes, and overcomes the undue bulging action which ordinarily results from such flanges.

The spring steel used in this construction is of the highest quality tempered steel, and is made to conform with the shape of the normal arch of a foot. This spring steel arch supporter, consisting of a pair of relatively movable plates is sufficiently strong to hold up the outer longitudinal arch of the foot, which is ordinarily the first part to fall.

It should be noted that the steel plates are properly encased in the leather casing, and that there are no holes or notches in these plates to weaken them. Consequently, they have maximum strength and allow the foot to move normally. A distinct advantage is that the support does not have any metal parts coming into contact with the shoe to cause unnecessary wear, or with the sock or sole of the foot, all of which would be objectionable. The well stitched leather casing is exceptionally strong and is not liable to become disrupted. These and other advantages and features of the invention have doubtless been made apparent by the foregoing description and drawings. Therefore, a more lengthy description of the invention is thought to be unnecessary.

While the preferred embodiment of the invention has been shown and described, it is to be understood that changes in the shape, size, and arrangement of parts may be resorted to if such changes come within the scope of the invention hereinafter claimed.

Having thus described the invention, what I claim as new is:

1. An arch supporter comprising curvilinear and resilient metal plates superposed one upon the other and freely movable endwise each with respect to the other, and means encasing said plates and having an opening whereby interference with play of the plates each with respect to the other is averted.

2. An arch supporter comprising a pair of substantially duplicate curvilinear and resilient metal plates arranged in superposed relation, and freely movable endwise each with respect to the other, a casing for said plate, said casing being made up of two plies of leather stitched together around their

marginal edges and stitched inward of said edges around said plates to provide an open end pocket for retaining said plates, said plates and casing being shaped to conform to 5 the bottom of the foot to be supported.

3. An arch supporter comprising curvi-linear and resilient metal plates superposed one upon the other and freely movable end-wise each with respect to the other, and 10 means encasing said plates and having an

opening whereby interference with play of the plates each with respect to the other is averted; the said encasing means having a pocket of slightly greater width than the plates and adapted to guide the plates in 15 endwise movement thereof and open at one end.

In testimony whereof I affix my signature.

CHARLES P. MAYHALI.
